WHEELED SOUNDING TOY IN THE FORM
OF A PIG

William Vasil Lichko, Cleveland, Ohio

Application February 28, 1950, Serial No. 146,778

3 Claims. (Cl. 46—45)

1

This invention relates to toy animals, and more particularly to a wheeled toy animal of the sounding type.

A main object of the invention is to provide a novel and improved toy animal which is simple in construction, which emits a low pitched sound similar to a pig's grunt responsive to movement of the animal, and which is inexpensive to manufacture.

A further object of the invention is to provide an improved toy pig which involves a relatively small number of parts, which is sturdy in construction, and which provides a low pitched sound similar to a pig's grunt responsive to movement of the pig in either a forward or a rearward direction.

Further objects and advantages of the invention will become apparent from the following description and claims, and from the accompanying drawings, wherein:

Figure 1 is a side elevational view, partly broken away, of a toy pig constructed in accordance with the present invention;

Figure 2 is a top plan view, partly in horizontal cross-section, showing the toy pig of Figure 1;

Figure 3 is an enlarged fragmentary cross-sectional detail view taken on line 3—3 of Figure 1;

Figure 4 is a fragmentary bottom view, partly in cross-section, of the toy pig of Figures 1 to 3;

Figure 5 is an enlarged fragmentary side elevational detail view of the rear portion of the wheeled frame forming part of the toy pig of Figure 1;

Figure 6 is a view similar to Figure 5, but showing the action of the sounding mechanism responsive to movement of the wheeled frame in a direction opposite to the direction of movement of the frame in Figure 5.

Referring to the drawings, the toy pig is designated generally at 11 and comprises an external housing simulating the appearance of a pig, said housing being secured on a wheeled frame 12. The frame 12 comprises a rectangular block formed with a large internal recess or cavity 13 which is open at the bottom of the block, as shown at 14. The recess 13 and the opening 14 define a sounding chamber adapted to transmit vibrations applied to the body 12 in a manner to be presently described. The rear wheels, shown at 15, 15, are mounted on an axle 16 rotatably secured in brackets 17, 17, said brackets being in turn secured to the bottom surface of the block 12 at its rear portion. Designated at 18 is a transverse shaft which extends rotatably

2

through the forward portion of the block 12 and has rotatably mounted on its ends the respective wheels 19 and 20. The wheel 20 is formed with inset gear teeth, shown at 21.

5 The outer housing 11 is secured to the rear portion of the block 12 by means of a transverse bracket 22 and is secured to the forward end of the block 12 by means of a second transverse bracket 23.

10 Designated at 24 is a magnet, which may be of circular shape as shown in Figure 2, said magnet being movably secured to the top surface of the block 12 at its intermediate portion by means of a pair of bolts 25, 25, said bolts being provided with coil springs 26 positioned between the heads of the bolts and the magnet 25 and resiliently bearing on the magnet, the bolts passing loosely through the magnet and the body 12 and being provided at their bottom ends with nuts 27. The rear end of the magnet 24 may be resiliently connected to the block 12 by a spring 28, one end of the spring engaging an eye 29 carried by the rear portion of the top of the magnet and the other end of the spring being engaged with an eye bolt 30 secured to the top wall of the block 12 rearwardly adjacent the magnet 24.

15 Designated at 31 is a forwardly extending arm of magnetic material having an apertured rear end, shown at 32, and extending through the aperture in the rear end of the arm is a transverse elastic band 33 secured around the bolts 25, 25 and held down by the springs 26, 26. The magnet 24 carries forwardly adjacent the respective bolts 25, 25 the outwardly directed hooked lugs 34, 34, and engaged around said lugs is another elastic band 35 which transversely overlies the arm 31, as shown in Figure 2.

20 The bottom edge of the arm 31 is formed with serrations, shown at 36, and the forward end of the arm comprises a triangular cam element 37, said cam element having respective top and bottom edges 38, 39 which are inclined with respect to each other, as shown in Figures 5 and 6. The edge 39 is substantially aligned with the bottom edge of the arm 31, whereas the top edge 38 is inclined forwardly and upwardly.

25 Secured to the block 12 forwardly adjacent the magnet 24 is an upstanding guide member of inverted U-shape, shown at 40, said guide member being aligned with and receiving the arm 31. As shown in Figure 5, the upper portion of the guide member 40 is bent rearwardly, as indicated at 41, to provide clearance for the triangular cam element 37.

30 Designated respectively at 42, 43 are upstanding brackets secured to the block member 12,

and journaled in said brackets is a transverse shaft 44 to the inner end of which is secured a vertical disc 45. Disc 45 carries diametrically opposed, inwardly extending pin elements 46, 46 adapted to cammingly engage the cam member 37 of the arm 31 responsive to rotation of the disc 45. As shown in Figure 5, when the disc 45 is rotated in a clockwise direction, the pin elements 46, 46 successively engage the bottom edge 39 of the cam member 37 and raise the arm 31 until the pin elements 46 rotate past the forward edge of the cam member 37, at which time the arm 31 is released. As the arm 31 is being elevated by a pin element 46, the elastic band 35 is stretched, and when the pin element 46 slips out from beneath the edge 39, the elastic band 35 returns the arm 31 into contact with the top surface of the magnet 24, the magnetic attraction of said magnet greatly reinforcing the action of the band 35, whereby the arm 31 strikes the surface of the magnet with considerable force, causing the arm 31 and magnet 24 to vibrate, and also causing the triangular cam element 37 to vibrate. The cam element 37 has a substantial area, the magnet is relatively heavy, and the arm 31 is relatively long, whereby the various vibrations produced by impact of the arm 31 with the top surface of the magnet are relatively low pitched, and when said vibrations are transmitted through the block 12 to the sounding cavity 13, the resultant sound simulates the grunting of a pig. A similar effect is produced when the disc 45 rotates counterclockwise, as shown in Figure 6, whereby the pin elements 46, 46 successively engage the inclined top edge 38 of the cam member 37, causing the arm 31 to pivot around the forward corner of the magnet 24, said pivotal action being provided by the engagement of one of the serration notches in the bottom edge of the arm 31 with said forward corner portion of the magnet. When the arm 31 is rotated downwardly by the camming engagement of a pin 46 with the top edge 38 of the cam member 37, as shown in Figure 6, the elastic band 33 is stretched upwardly, and when the pin element 46 slips past the cam edge 38, the arm is released and the elastic band 33 pulls the arm back toward its normal horizontal position, and at the same time the attractive force of the magnet greatly increases the impact force with which the arm strikes the top surface of the magnet. When the rear portion of the arm strikes the top surface of the magnet, vibrations are developed in the arm, in the magnet, and in the triangular cam element 37, said vibrations being similar to the aforementioned low-pitched vibrations produced when the disc member 45 is rotated in a clockwise direction.

The outer end of the shaft 44 carries a relatively large gear 47 which meshes with a small gear 48 carried on a transverse shaft 49 rotatably supported on vertical arms 50, 50 carried by the bracket 43. Secured on the outer end of shaft 49 is a relatively large gear 51 which meshes with the inset gear teeth 21 of the wheel 20. The disc 45 is therefore coupled to wheel 20 by the shaft 44, the gear 47, the small gear 48, the gear 51 and the gear teeth 21. Therefore, movement of the toy along the floor in either direction causes disc 45 to be rotated, and such movement produces vibration of the arm 31, the magnet, and the cam element 37, as above described, by the engagement and release of the pin elements 46 with the cam element 37. The low-pitched sounds produced by vibration of the arm 31, the magnet, and said cam element 37 are very similar

to the grunting of a pig, and therefore the sound produced by the toy animal responsive to movement thereof is very lifelike and entertaining.

The nose of the pig-shaped housing 11 is provided with a ring 52 to which a string 53 may be tied, whereby the pig may be drawn along the floor by pulling on the string 53.

While a specific embodiment of a sounding toy animal has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a sounding toy of the character described, a frame, a plurality of wheels journaled to said frame, a magnet mounted on said frame, an arm of magnetic material, resilient means yieldably connecting one end of said arm to the intermediate portion of the top of said magnet, means biasing said one end of the arm downwardly into contact with the top of the magnet, 20 a vertical member rotatably mounted on said frame for rotation around a horizontal axis, the plane of said member being parallel to the arm, a projection on said member cammingly engageable with the other end of said arm and arranged to move a portion of the arm away from the magnet, said arm being arranged to slip out of engagement with said projection during the cycle of rotation of said member, whereby the released arm is attracted toward and strikes the magnet, causing the arm to vibrate, and means coupling said member to at least one of the wheels of the frame.

2. In a sounding toy of the character described, a frame, a plurality of wheels journaled to said frame, a magnet mounted on said frame, 40 an arm of magnetic material, resilient means yieldably connecting one end of said arm to the top of said magnet, an elastic band secured transversely on the magnet and transversely overlying said one end of the arm biasing said one end of the arm downwardly into contact with the top of the magnet, the lower edge of said arm being serrated, whereby the arm may at times pivot on the edge of the magnet, a vertical disc rotatably mounted on said frame for rotation around a horizontal transverse axis, a plurality of spaced projections on said disc cammingly engageable with the other end of said arm and arranged to move a portion of the arm away from the magnet, 50 said arm being arranged to slip out of engagement with said projections during the rotation of said disc, whereby the released arm is pulled toward and strikes the magnet, causing the arm to vibrate, and a gear train carried by the frame 55 and coupling the disc to one of the wheels of said frame.

3. In a sounding toy of the character described, a frame, a plurality of wheels journaled to said frame, a magnet yieldably secured to said frame, 65 an arm of magnetic material, resilient means yieldably connecting the rear end of said arm to the top of said magnet, an elastic band secured transversely on the magnet forwardly of said means and transversely overlying said rear end 70 of the arm, biasing said rear end downwardly into contact with the top of the magnet, the lower edge of said arm being serrated, whereby the arm may at times pivot on the edge of the magnet, a vertical triangular cam carried at the 75 forward end of said arm, a vertical disc rotatably

mounted on said frame for rotation around a horizontal transverse axis, a plurality of spaced projections on said disc engageable with the edges of said cam and arranged to move a portion of the arm away from the magnet, said cam being arranged to slip out of engagement with said projections during the rotation of said disc, whereby the released arm is pulled toward and strikes the magnet, causing the arm, magnet and cam to vibrate, and a gear train carried by said frame and coupling the disc to one of the wheels of said frame. 10
